UNITED STATES PATENT OFFICE.

JAMES W. IVORY, OF PHILADELPHIA, PENNSYLVANIA.

TOBACCO PIPE.

Application filed December 4, 1919. Serial No. 342,568.

To all whom it may concern:

Be it known that I, JAMES W. IVORY, a subject of the King of Great Britain, residing in the city and county of Philadelphia, 5 State of Pennsylvania, have invented a new and useful Tobacco Pipe, of which the following is a specification.

My invention relates to an improvement in ordinary tobacco pipes whereby tobacco may 10 be smoked dry and comfortable while avoiding clogging of the base of the bowl and stem of the pipe, preventing gurgling in the pipe and overcoming an excess of nicotine juice forming in the base of the bowl and 15 stem of the pipe, and steaming of the tobacco and smoke are avoided. These and other advantages are achieved by means of an inner bowl placement consisting of a vessel or tray, and an extra fresh air passage, or extra air passages by means of a 20 perforated stem on the bowl, or through a perforation in the wall of the bowl at the base thereof through or around said placement, whereby said air mingles with the 25 smoke after the latter is created and leaves the burning tobacco, as will be hereinafter more fully set forth.

The invention is satisfactorily illustrated in the accompanying drawings, but the important instrumentalities thereof may be 30 varied, and so it is to be understood that the invention is not limited to the specific details shown and described, as long as they are within the spirit or scope of the claims.

Figure 1 represents a longitudinal vertical section of a tobacco pipe embodying my invention.

Figure 2 represents a side elevation of a placement member detached from Figure 1.

Figure 3 represents a vertical section of another embodiment of the invention.

Figure 4 represents a transverse section on line 4—4 Figure 3.

Figures 5, 6, and 8 represent longitudinal sections of other embodiments of the invention.

Figure 7 represents a bottom plan of the placement existing in Figure 6 as removed therefrom.

Similar numerals of reference indicate corresponding parts in the figures.

Referring to the drawings,

1 designates the bowl of a tobacco pipe, and 2 designates the stem proper thereof. 55 3 designates a placement in the bottom por-

tion of the bowl on which the tobacco is supported, the same consisting of a vessel or tray having in the circumference thereof the channel 4, the vertical ports 5 leading to said channel and the threaded vertical opening 6 in which may be screwed the end of the stem 7, whereby said placement may be located in position and removed therefrom as desired.

In the portion of the wall of the bowl opposite to the stem 2 is an enlarged orifice 8 which receives the adjacent end of the supplemental stem 9 which extends outwardly from said wall and has its bore 10 in communication with the circumferential channel 4 of the placement.

In said placement 3 is the horizontal passage 11 which is in communication with the ports 5 and the bore of the stem 2, it being seen that the placement supports the tobacco and prevents clogging of the base of the bowl while an extra volume of fresh air is drawn into the bowl by the supplemental stem 9 and commingles with the smoke after the latter leaves the burning tobacco in connection with the air being drawn through the open top of the bowl as usual and passing through the tobacco an extra volume of air then being drawn into the stem proper and from thence into the mouth thus providing a dry and comfortable smoke.

Various other forms of accomplishing the above results are shown in the other figures as follows:—

In Figures 3 and 4 the supplemental stem 9 is extended through the base portion of the bowl under the perforated placement 3, and joins the neck 12 of the bowl. A chamber 13 exists in the base of the bowl below the interior portion of the supplemental stem 9, and a channel 14 exists around said portion of the stem 9 the same being in communication with said chamber 13. In the wall of said supplemental stem 9 is the port 15 which forms a communication for the bore of the supplemental stem with said chamber 13 so that smoke is drawn in said bore and commingles with the air entering said bore. In the base portion of the bowl is the additional port 16 which communicates with the atmosphere and the chamber 13 and admits additional air to the latter.

In Figure 5, the supplemental stem 9 is continuous of the stem 2 and the bores of 110

said stems are also continuous. The placement has its perforations 17 in communication with the channel 18 around the supplemental stem 9 whereby smoke is directed 5 to the chamber 19 in the bottom of the bowl, the smoke then entering the bore 10 in the supplemental stem 9 through the port 21 in the latter.

In Figures 6 and 7 the placement consists 10 of a block with a recess 22 in the underside of its wall forming the flanges 21 which rest on the bottom of the bowl, the sides of said tube being cut away as at 22* whereby the smoke may pass around said sides and enter 15 the said recess.

An auxiliary stem 23 is provided, the same entering the placement serving to hold the latter in position and communicating with the recess 22 whereby air may be admitted into the latter and commingle with the smoke in its passage to the stem proper.

In Figure 8 a portion of the auxiliary stem enters the base of the bowl the portion within said base being adapted to support the placement thereon and has the passage 28 around the same to receive the smoke from the bowl which is directed by the end of said passage as at 29 into the bore of the neck of the bowl. Air is directed through 30 the bore 10 of said auxiliary stem to the bore in said neck and so commingled smoke and air are directed into the stem proper.

It will be seen that in Figures 3, 4, and 5, the placements are supported on the inner 35 end of the supplemental stems 9. In Figures 6 and 7, the placement is tubular and fitted on and so supported by the inner end of the supplemental stem, said placement having therein the recess 22 whereby the 40 placement is in communication with said supplemental stem and the stem proper.

It will be seen also that while the placements are supported on the supplemental stem the tobacco will be placed on said 45 placements and so prevent the clogging of the bottom of the bowls.

Furthermore as a volume of fresh air is

drawn into the bowl through supplemental stems and it mingles with the smoke drawn from the bowl the smoking will be easy, 50 dry, comfortable and enjoyable, obviating steaming of the smoke and tobacco in the bottom of the bowl and clogging in said bottom, and the bore of the stem proper of the pipe and preventing an excess of nicotine entering said stem proper, and there will be no gurgling of solutions in the base 55 of the bowl and in the stem.

The placement may be readily removed from the bowl by the handle 7, Figure 2, to 60 the same in the opening 6, Figure 1, so as to cleanse the placement or supply a fresh placement to the one that has been in use.

In some cases I provide an additional air supply by means of an extra port or aperture 65 16 as in Figure 3.

In some cases when it is desirable to hold the placement in position other than by the inner wall of the bowl, I employ the screw 70 39 which is passed upwardly through the bottom of the bowl into the placement, the head of the screw being on the underside of said bottom where it is convenient of access, as shown in Figure 1.

Having thus described my invention what 75 I claim as new and desire to secure by Letters Patent, is:—

1. In a smoking pipe, a bowl, a stem, an auxiliary air supplying means, the latter in communication with said bowl and said 80 stem, and a perforated placement in the bowl in communication with said bowl and in contact with said auxiliary air supplying means.

2. In a smoking pipe, a bowl, a stem, and 85 an auxiliary air supplying means, the latter having on its exterior in the portion within the bowl a chamber which is in communication with said bowl and with said stem.

JAMES W. IVORY.
